UNITED STATES PATENT OFFICE.

HENRY DAVIS, OF DERBY, ENGLAND.

ANEMOMETER.

1,050,350.

Specification of Letters Patent. Patented Jan. 14, 1913.

Application filed June 18, 1912. Serial No. 704,271.

To all whom it may concern:

Be it known that I, HENRY DAVIS, a subject of the King of Great Britain and Ireland, and resident of All Saints Works, Amen Alley, in the county borough of Derby, England, (whose post-office address is All Saints Works, Amen Alley, Derby, England,) have invented certain new and useful Improvements in Anemometers, (for which I 10 have applied for a patent in Great Britain, said application being numbered 17,075 and dated July 26, 1911,) of which the following is a specification.

The objects of my invention are to obtain 15 a sensitive instrument of the least possible diameter and one that may without difficulty be held so that the operator's body or arm will not impede or deflect the current of air: and further, to obtain a dial which may 20 be easily and therefore accurately read.

Referring to the drawings which form a part of this specification:—Figure 1 is a sectional elevation on line *a—a* of Fig. 2. Fig. 2 is an elevation of my improved anemometer from the dial side.

In carrying out my invention I cause the fan *b* to be larger in proportion to the size 30 of the instrument than usual, said fan starting approximately at the central shaft *c* and extending to the outer protecting ring *d*: I employ a deflecting cone *e* with its apex adjacent the fan and enlarged toward its 35 base to substantially the inside diameter *d'* of the outer protecting ring *d* of the instrument. An annular port *g* is formed in the

said protecting ring or casing to admit of the free exit of the air passed through the vanes and deflected by the cone in the direction of the arrows on Fig. 1, as already set forth: the deflection of the air from the 40 person of the operator insuring accurate working of the instrument.

The unit indicating dial *f* coming at the back of the base of the deflecting cone may be made the full diameter of the protecting 45 ring *d*, and so enable small quantities or currents of air to be measured with accuracy. The inside of the cone contains the train of wheels for operating the indicating dials.

Having now described my invention, what I claim as new and desire to secure by Letters Patent is:—

In an anemometer, in combination, a fan of large proportions, an outer casing or 55 protecting ring wherein said fan is mounted, said casing carrying a deflecting cone, there being an annular port between said ring and said cone, the internal part of said cone containing a train of wheels and the base of 60 said cone being fitted with a dial the unit ring of which approximates the size of the protecting ring.

In testimony whereof I have signed my name to this specification in the presence of 65 two subscribing witnesses.

HENRY DAVIS.
